UNITED STATES PATENT OFFICE.

THOMAS HENRY BELLOWS, OF WALLA WALLA, WASHINGTON.

CAR-REPLACER.

1,364,913.

Specification of Letters Patent. Patented Jan. 11, 1921.

Application filed June 21, 1920. Serial No. 390,484.

To all whom it may concern:

Be it known that I, THOMAS HENRY BELLOWS, a citizen of the United States, residing at Walla Walla, in the county of Walla 5 Walla and State of Washington, have invented a new and useful Car-Replacer, of which the following is a specification.

This invention relates to railway appliances, and more particularly to rerailing devices for replacing cars on the rails of a track, after a car has been derailed.

An object of the invention is to provide a device of this character which may be readily and easily applied adjacent to a rail for 15 receiving the wheels of the car being replaced, the construction of the device being such as to guide the wheels onto the track.

A further object of the invention is to provide means for preventing lateral movement of the device when a car is moving 20 over the same.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:—

Figure 1 illustrates a side elevational view of a replacer constructed in accordance with 30 the present invention.

Fig. 2 illustrates a plan view of the same.

Fig. 3 illustrates a sectional view taken on line 3—3 of Fig. 1; and

Fig. 4 illustrates a sectional view taken 40 on line 4—4 of Fig. 2.

Referring to the drawing in detail, the device includes a body section 5 and a removable rail section 6, the body section being relatively wide, and provided with a 45 flange 7 formed in spaced relation with one of the side edges thereof, the wall connecting the flange 7 and body section being curved as at 8 to accommodate the usual flange of a car wheel.

50 The upper portion of the body section 5 is curved as at 9, the opposite edge thereof being inclined as at 10, to provide a camming surface for coöoperating with the flange of a wheel to guide the wheel to the track, 55 the inclined surface 10 being however dis-

posed on the side of the body section 5, which in operation is positioned adjacent to the rail.

Spaced arms 11 are formed at each end of the body section 5, which arms are provided 60 with openings to accommodate the pin 12, which pin 12 also passes through a suitable opening provided in the tongue 13 that forms a part of the movable rail section 6, there being provided a cotter pin 14, extending 65 through an opening in the pin 12 to prevent displacement of the pin, while in operation.

The upper surface of the track sections 6 is inclined toward the outer extremity thereof so that the least possible resistance will be directed to the car being replaced, by the replacer, and aid in the replacing of the car. An opening 15 is formed transversely of the rail section 6 and accommodates the 70 arm 16 which is provided with a plurality of openings 17 disposed in spaced relation with each other, which openings are designed to accommodate the pin 18 which in operation lies flush with one wall of the 75 rail section 6 to prevent movement of the arm 16 within the opening.

Associated with the arm 16 is a hook member 19 adapted to be positioned under the base of a rail as indicated by Fig. 4 of 85 the drawing, a portion of the base of a rail being indicated by the reference character 20, and it will be seen that this hook member 19 has connection with the arm 16 through the medium of the link 21 and relatively small hook 22, which hook 22 passes 90 through the opening 23 formed in the hook member 19, so that the hook member may be readily and easily disconnected from the arm 16.

95 From the foregoing it is obvious that when the hook member 19 is positioned under the base of a rail, lateral movement of the device is prevented; however to further insure against lateral displacement of the device, the pins or spikes indicated at 24 are provided, which pins are formed integral with the under surfaces of the base section, and rail section, and are designed to embed themselves in the ties which support the rail 100 associated with the device.

In view of the fact that the body section 5 is provided with spaced arms 11, at its respective ends, it is obvious that the rail section 6 may be disconnected from one end of 110

the body section 5, and connected to the opposite end thereof, thus providing a replacer or rerailer adapted for unlimited use.

Having thus described the invention, what I claim as new is:—

In a device of the character described, a base section having spaced arms formed at the respective ends thereof, a rail section having an extension adapted to be positioned between the arms at one end of the base, said rail sections having an opening extending transversely therethrough at a point substantially intermediate the ends thereof, a

locking means including a hook member, an arm having connection with the hook member, said arm adapted to pass through the transversely extending opening, and means to restrict movement of the arm within said opening.

In testimony that I claim the foregoing as my own, I have hereto affixed my signature in the presence of two witnesses.

THOMAS HENRY BELLOWS.
